(57) **CLAIM**

The ornamental design for a rear frame for a riding-type mower, as shown and described.

DESCRIPTION

FIG. 1 is a perspective view of a rear frame for a riding-type mower according to the invention;

FIG. 2 is a front elevation view of the rear frame for a riding-type mower of FIG. 1;

FIG. 3 is a rear elevation view of the rear frame for a riding-type mower of FIG. 1;

FIG. 4 is a right-side elevation view of the rear frame for a riding-type mower of FIG. 1;

FIG. 5 is a left-side elevation view of the rear frame for a riding-type mower of FIG. 1;

FIG. 6 is a top plan view of the rear frame for a riding-type mower of FIG. 1; and,

FIG. 7 is a bottom plan view of the rear frame for a riding-type mower of FIG. 1.

The broken line disclosure, as well as shading in parts of the drawings is included for the purpose of illustrating use and environment and forms no part of the claimed design.

1 Claim, 7 Drawing Sheets
